(57) **CLAIM**

The ornamental design for an analysis device, as shown and described.

DESCRIPTION

FIG. 1 is a front, right perspective view of an analysis device of the present design;

FIG. 2 is a front, left perspective view thereof;

FIG. 3 is a front view thereof;

FIG. 4 is a rear view thereof;

FIG. 5 is a top view thereof;

FIG. 6 is a bottom view thereof;

FIG. 7 is a right side view thereof, the left side view being a mirror image thereof; and,

FIG. 8 is a front, right perspective view thereof with a lid of the analysis device shown in an open configuration.
